UNITED STATES PATENT OFFICE.

GEORGE P. TILTON, OF NEWBURYPORT, MASSACHUSETTS, ASSIGNOR TO TOWLE MANUFACTURING COMPANY, OF NEWBURYPORT, MASSACHUSETTS, A CORPORATION OF MASSACHUSETTS.

DESIGN FOR A SPOON, FORK, OR SIMILAR ARTICLE.

40,372.

Specification for Design.

Patented Nov. 30, 1909.

Application filed August 30, 1909. Serial No. 515,370. Term of patent 14 years.

To all whom it may concern:

Be it known that I, GEORGE P. TILTON, a citizen of the United States, residing at Newburyport, in the county of Essex and State of Massachusetts, have invented a new, original, and ornamental Design for Spoons, Forks, or Similar Articles, of which the following is a specification, reference being had to the accompanying drawings, forming a part thereof, wherein—

Figure 1 is a plan view showing the obverse side of the spoon; Fig. 2 is a plan view showing the reverse side of the spoon; and Fig. 3 is an edge view.

The design consists in the spoon, fork, or similar article ornamented by the mayflower or arbutus which appears on both

sides, as shown in the drawings. In Fig. 1 a cluster of the flower tied with a ribbon appears near the tip of the handle and a spray at the juncture of the handle with the bowl. In Fig. 2 a larger spray appears on the back of the bowl. Superimposed over this larger spray appears a shield upon which is the conventional figure of an ancient sailing vessel and the date 1620, and beneath the shield appears the word "Mayflower."

I claim—

The ornamental design for a spoon, fork, or similar article, as shown and described.

GEORGE P. TILTON.
